BUNDLED PACKAGE

Victor J. Mueller, Peoria, Ill., assignor to W. A. Laidlaw Wire Co., Peoria, Ill., a corporation of Illinois

Application September 1, 1934, Serial No. 742,465

1 Claim. (Cl. 206—46)

This invention has reference to the wrapping and securing preferably wire bale ties in bundle form made ready for shipment or storage purposes, however, materials other than wire bale

5 ties may be wrapped and secured in like fashion if desired and no limitation of materials used is herein intended.

In the wrapping and securing of preferably wire bale ties in bundle form, it is recognized that

10 many wrapping variations have been employed, particularly, such bale tie bundles employing wrappings comprising a single wire wound spirally and continuously around the length of the bundle and having the ends of such wire beginning and terminating at the opposite ends of the bundle and secured thereto.

Bale tie bundles of the wire type, finished in black or galvanized wire, as the case may be, most generally consist of 250 lengths of bale ties 20 of a well known type, each tie having an eye or loop formed at one end while the opposite end of the tie is left straight. Such lengths of bale ties are preferably arranged in parallel relation to each other with the eyes or loops at one end and 25 the straight ends at the opposite end. It will be understood that bale tie bundles of this type are furnished in various lengths and gauges of wire and are of considerable weight. It is important therefore, the bale tie bundles, when prepared 30 for shipment or storage or other bundle handling, be compacted in bundle form by a most secure wrapping arranging whereby to insure the bale ties in the bundles from segregating and necessitating reparation causing possible waste, damage and expense.

The principal object of the present invention resides in an improved mode of wrapping and securing bale ties in bundle form consisting essentially of a wire strand initially locked at one end of the bundle and spirally wound continuously around the length of the bundle to the opposite end thereof, looping said strand about said opposite end and overlapping said initial spiraled length by returning said strand spirally and continuously thereof to form diamond-like sections in the strand wrap about the length of said bundle and locking the end of said strand to said first end of the bundle. This character of wrap for a bale tie bundle has been found to be most successful in many ways, i. e., to present a firmer and tighter bundle throughout its length and minimizes the possibility of loosened and lost ties in the bundles when subjected to considerable handling and rough treatment; the elongated

spirally wound wire strand when released for unpacking the bundle, is a safeguard against live stock swallowing it by reason of its extended length.

Other and further objects will more fully appear from the following description.

That the invention may be more fully understood, reference is had to the accompanying drawing illustrating a preferred embodiment of the invention, in which:

Fig. 1 is a plan view of a wire bale tie bundle employing my improved mode of wrapping and securing the same;

Fig. 2 is an enlarged fragmentary view of one end of the bale tie bundle, shown in Fig. 1, and

Fig. 3 is an enlarged fragmentary view of the other end of the bale tie bundle, shown in Fig. 1.

Like characters of reference denote corresponding parts throughout the figures.

Referring now to the drawing, I accomplish 20 the completed bale tie bundle illustrated in Fig. 1, ready for shipment, storage or other handling, by assembling together in parallel relation a plurality of wire bale ties 1, each formed at one end with the usual eye or loop, not shown, while the 25 opposite end, not shown, is left straight, the loop ends of the bale ties 1 being arranged at one end with the straight ends at the other end. The loop ends of the bundle are preferably first compacted together by means of a short length of 30 wire 2 passed therearound and the ends twisted together as at 3 and then bent flat against the side of the bundle, said wire and twisted ends being shown in dotted lines in Figs. 1 and 2.

The straight ends of the bundle of bale ties are 35 next covered with a preferably flexible protective covering 4, such as burlap, and is secured thereto by means of a short length of wire 5 which is given one turn around the sides of the burlapped end of the bundle and the ends twisted together, 40 as at 6, and then bent flat against the side of the bundle, as shown in Figs. 1 and 3.

Referring now particularly to the left hand end or looped bale tie end of the bundle in Fig. 1, and 45 to Fig. 2, an elongated single strand of wire 7 is provided having a hooked end 8 fastened about the looped wire 2, the remaining length of the wire 7 extending loose and preferably in the direction of the length of the bundle, whereupon, a like flexible protective covering 9, such as burlap, is placed over and around the compacted looped ends of the bundle of bale ties and is secured thereto by means of a short length of wire 10 which is given 50 one turn around the sides of the burlapped end of 55

the bundle and the ends thereof given an initial twist at 11 to hold the burlap in placement over the looped end of the bundle.

Next, the extended loose length of the wire strand 7 is bent backwards creating the fold 12 in the burlap covering 9 and is folded sharply over the wire loop 10 at 13 and then extended substantially centrally around the covered end of the bundle at 14 and thence forwardly again 10 on the opposite side, as indicated in dotted lines, in a more or less diagonal direction to the skirt end of the protective covering at 15 from which point the wire strand 7 is tightly wound spirally and continuously around the length of the bundle 15 towards the opposite or straight end of the bale ties forming the bundle, see Figs. 1 and 3. Upon the strand 7 approaching the skirt end of the protective covering 4 at such opposite end, it is bent somewhat sharply as at 16 in a diagonal 20 direction and is laid tightly over the looped wire 5 and then sharply looped around the covering 4 at 17. The looped portion 17 of the wire strand 7 is preferably located next adjacent the tightly looped wire 5 between such looped wire 5 and 25 the straight end of the bundle, best seen in Fig. 3. The location of the looped portion 17 next adjacent the looped wire 5 is desirable in order to prevent displacement of said looped portion in a direction towards the other end of the bundle 30 and cause looseness in the finished wrap; further, it is desirable to insure the protective covering 4 being tightly and securely applied to the straight end of the bundle.

Following the looping of the wire strand 7 at 35 17, it is then extended similarly backwards diagonally across the looped wire 5 overlapping itself at 18 and upon reaching the skirt end of the protective covering 4 at 19, said wire strand 7 is again tightly wound spirally and continuously 40 around the return length of the bundle, overlapping itself first on one side and then the other, as at 20, to form diamond-like connected sections in the wrap. Upon reaching the looped end of 45 the bundle of bale ties, the wire strand 7 is twisted about the extended twisted ends 11 of the looped wire 10 and the combined ends of the wires 10 and 7 are tightly twisted together to form the finished knot 21, whereupon any uneven ends of 50 such wires are cut off and the finished knot is preferably bent flat against the covered side of the bundle, as shown in Figs. 1 and 2.

As will appear obvious, a bale tie bundle wrapped and secured in the above described fashion produces a bundled package ready for ship-

ment, storage or other handling capable of the most severe punishment incident thereto without chance of becoming disarranged or loose, yet simple in application and easy to the consumer for unwrapping with a minimum amount of small length wires to salvage.

The novel mode of spirally and continuously winding of a single strand of wire originating at one end and extending spirally the length thereof and back again in like fashion, forming 10 as it does the diamond-like sections in the spiral wrap, makes the bundled package throughout its length most compact and rigid and eliminates the usually prevalent bulging portions in the length of the material wrapped, and thereby 15 presents no surfaces in the wrapped length upon which other articles or materials might catch upon and as a result thereof, distort, loosen and possibly break the packaged material, as will be understood.

What I claim is:

A bundled package including the combination of material arranged in compact relation, a relatively short binding strand looped and fastened about said material adjacent one end thereof, a 25 flexible protective covering secured about said end in overlapping relation by means of a separate relatively short binding strand looped and fastened therearound, a flexible protective covering secured about the other end thereof in similar 30 overlapping relation by means of a relatively short binding strand looped and fastened therearound, a relatively long separate binding strand having an end hooked to said first mentioned short binding strand located beneath said first 35 mentioned protective covering and extended out from beneath said covering and bent over said short binding strand of the flexible covering and thence exteriorly over said end covering and thence wound spirally and continuously around the length of the body of said material in spaced 40 relation to said other covered end thereof, looping said long strand transversely about said covered end and thence reversing the uninterrupted length of travel of said long strand to said first 45 mentioned covered end by spirally and continuously winding said long strand in spaced relation over said initial spirals to form diamond-like sections in said spiral wraps about the material, and fastening the loose end of said long strand to the short binding strand serving as a fastener for said first mentioned flexible covering.

VICTOR J. MUELLER.
